UNITED STATES PATENT OFFICE.

FRANK M. STEINER, OF MINNEAPOLIS, MINNESOTA, ASSIGNOR TO STEINER SALES COMPANY, OF SALT LAKE CITY, UTAH, A CORPORATION OF UTAH.

TOWEL CABINET.

Application filed August 25, 1921. Serial No. 495,383.

To all whom it may concern:

Be it known that I, FRANK M. STEINER, a citizen of the United States, resident of Minneapolis, in the county of Hennepin and 5 State of Minnesota, have invented certain new and useful Improvements in Towel Cabinets, of which the following is a specification.

The object of my invention is to provide 10 means in connection with a towel cabinet or support to cause the toweling that is drawn off from one roll generally designated the "clean towel roll" to be automatically wound upon another roll generally designated 15 the "soiled towel roll," and at the same time so arranged that by pulling down on the toweling, clean toweling can be obtained for the user, and by pulling out on the toweling slack may be obtained from the 20 lower roll for convenience when using the towel.

A further object of the invention is to provide means whereby when an extra amount of toweling has been pulled to the 25 front by the user, and left as a fold or slack portion hanging out of the cabinet, the same will be wound upon the soiled towel roll by the action of the user in drawing or pulling a fresh section of toweling 30 from the clean towel roll into position for use.

The invention consists generally in the constructions and combinations hereinafter described and particularly pointed out in 35 the claims.

In the accompanying drawings forming part of this specification,

Figure 1 is an end elevation of a towel cabinet embodying my invention,

Figure 2 is an elevation and partial section, the view being taken on line 2—2 of Figure 3, looking in the direction of the arrows,

Figure 3 is a vertical section on line 3—3 of Figure 2, the toweling being shown in full lines in its normal position, and being shown in dotted lines drawn forward and partially pulled out of the front of the cabinet,

Figure 4 is an elevation of the upper

portion of the opposite end of the cabinet from the shown in Figure 1,

Figure 5 is a vertical section on line 5—5 of Figure 4,

Figure 6 is a section on line 6—6 of 55 Figure 7, and

Figure 7 is a section on line 7—7 of Figure 6, showing a modified construction.

In the drawings, 2 represents the cabinet which is ordinarily made of sheet metal, 60 though material of any other kind may be employed in its construction. As here shown the cabinet is provided with a lower section or compartment 3, having a door 4 in each end. The cabinet is preferably supported upon suitable standards or legs 6—6. The compartment 3 is provided with an opening or slot 7 preferably located in the upper portion of its rear wall, and it is adapted to contain the roll of clean toweling 70 8 that is placed loosely in said compartment. The upper section 9 of the cabinet is preferably secured to or formed integrally with the lower section 3, as shown in Figure 3.

The rear portion of the cabinet is provided with a wall 11 which preferably extends, as here shown, about two-thirds of the height of the upper section of the cabinet. A roll 12 is arranged upon a shaft 13 that is mounted in bearings in the end 80 walls of the upper section of the cabinet (Figure 4) and a winding up roll for the soiled toweling is mounted in bearings in the lower part of the upper section of the cabinet. The lower front wall 15 of the 85 upper cabinet section extends preferably about two-thirds of the height of said section, and an opening is left above this wall extending nearly to the top of the section where it is closed by a suitable mirror 16 90 preferably secured between the end walls of said upper section. The shaft 13 of the roll 12 is preferably provided with a belt pulley 17 and a similar pulley 18 is provided on the shaft of the winding up roll 14 (Figure 2). 95 At the upper end of the wall 11 the toweling passes behind a bar 21 and thence over the roll 12, and down to the roll 14 upon which the soiled towel is wound. A belt 22 passes around the pulleys 17 and 18. I have here 100

shown the belt 22 crossed between the pulleys so that the roll 17 is driven in one direction, and the roll 18 in the opposite direction as shown in Figure 3 of the drawings.

I prefer to make the pulley 18 considerably smaller in diameter than the pulley 17, so that the roll 14 is rotated much more rapidly than the roll 12.

10 It will be seen that by pulling down on the portion of toweling that is exposed through the open front of the cabinet, the roll 12 will be rotated upon its axis, and the roll 14 will be rotated in the opposite direction, and at a considerably greater speed than the roll 12. As the toweling is unwound from the clean towel roll, and passed over the roll 12, which may be designated the "driving roll," it is wound upon the 15 roll 14.

I adjust the belt 22 with respect to the pulleys 17 and 18, so that the friction between the belt and the pulleys is sufficient to cause the toweling that is pulled over 20 the roll 12 to be wound upon the roll 14, while at the same time the friction between the belt and the pulleys is light enough to permit slipping between the same when the surface speed of the roll of toweling on 25 the winding up roll 14 is greater than the surface speed of the roll 12.

It will be seen, therefore, that the belt 22, with the pulleys 17 and 18, provide a friction drive from the roll 12 to the roll 30 14, which permits sufficient slippage to prevent any strain upon the toweling between the rolls beyond what is required to cause the toweling drawn over the roll 12 to be smoothly wound upon the roll 14.

40 Moreover, should the user desire to bring the toweling outward through the open front of the casing, producing a slack or loop therein, as indicated by dotted lines in Figure 3, he may accomplish this by 45 pulling outward on the toweling, thereby reversing the roll 14 and drawing the toweling therefrom, the slippage of the belt permitting such reverse motion of said roll 14. If the user drops the slack portion of the 50 toweling, after pulling it out in this manner, it will hang over the edge of the front wall of the cabinet, as indicated by the dotted lines in Figure 3. When, however, the user pulls down on the toweling so as 55 to expose a clean or fresh portion thereof, thereby rotating the roll 12, the roll 14 will be more rapidly rotated and the slack part of the toweling will be quickly wound thereon.

60 I do not limit myself to the particular form of friction roll 12 and the roll 14. Any suitable friction drive that will permit the required slippage between the belt and the pulleys of the rolls 12 and 14 may be 65 employed to obtain the same movement of

the rolls, and the same winding action of the toweling.

I have shown the belt 22 crossed between the pulleys 17 and 18. If preferred, however, a straight belt may be used between 70 these pulleys instead of the cross belt herein shown.

To increase the friction between the toweling and the surface of the roll 12 over which said toweling passes, I prefer 75 to locate the bar 21 at a point under the roll 12, as indicated in Figure 3, thereby throwing the toweling inward towards a vertical line passing through the shaft of the roll 12, and increasing the contact surface between the toweling and the roll. The position of this bar also increases the friction upon the toweling and prevents any slackness therein between the roll 12 and the supply roll in the bottom of the cabinet. 85

In order to limit or measure the amount of toweling that will be pulled from the roll by a user, I prefer to provide in connection with the roll 12 a stop that will check said roll, when a complete revolution 90 thereof has been made by pulling the toweling over said roll and thereby rotating the same. The stop device that I prefer to use for this purpose, and which is illustrated particularly in Figures 4 and 5 of the 95 drawings is substantially the same as that shown in Patent No. 1,287,786, issued to G. A. Steiner, December 17th, 1918, and also shown in the pending application of said G. A. Steiner, Serial No. 442,127, filed February 23rd, 1921. This stop device comprises a disc or plate 24 having in the face thereof a groove 25 with the abrupt stop or shoulders 26, 27. This plate is secured to the wall of the cabinet, with the shaft 13 projecting through said plate and provided with a crank 28 having a handle 29, and slide 30 carrying a lug 31 that engages the groove 25 in the plate 24. When the roller 12 is rotated, by pulling on the toweling through the open face of the cabinet, the crank 28 is also rotated, the lug 31 extending into and following the groove 25 in the plate 24. As the crank arm 28 rotates with the shaft 13 the lug 31 travels along in the groove 25, and when the shaft has made a complete revolution, from its normal stopping point, said lug 31 will strike against the shoulder 26 and quickly stop the rotation of the roll 12. This 100 rotation of the roller 12 will measure off the toweling material that has been drawn over the roll 12. 110

115 It will be seen that the slide 30 is mounted loosely in a slot in the crank 28, so that 120 said slide may freely move back and forth, carrying the lug 31, and may accommodate itself to the varying diameter of the plate or disc 24.

125 This temporary stoppage of the toweling, 130

by the checking of the roller 12 does not prevent said device from being operated again immediately or as soon as the lug 31 has been released by contact with the 5 shoulder in the groove. As the shoulder 26 is at the top of the plate 24 (see Figures 4 and 5), as soon as the pull is released on the toweling the slide 30 will drop downward and inward across the end 10 of the shaft 13, and will carry the lug 31 out of contact with the shoulder 26, and into the part of the groove immediately opposite the shoulder 27. The roll 12 will, therefore, be free to make another revolution when impelled by a further pulling 15 movement on the toweling depending from said roll.

If the measuring stop device is employed a user pulling outward on the toweling, 20 after he has pulled the toweling a sufficient distance to cause the movement of the roll 12 to be stopped by the movement of the stop device, will reverse the movement of the roll 14, and he must pull all of the 25 toweling he desires to bring out of the opening in the cabinet from said roll, the roll 12 being locked against further movement by the device described.

In Figures 6 and 7 I have shown a modified construction in which the lower compartment 3 is dispensed with and the clean toweling 8 is placed on a roll 33, located near the top of the cabinet and prevented from rotating too freely by a heavy roller 34, having gudgeons 35 arranged in vertical grooves 36 in the wall of the cabinet, which in this instance is indicated as of considerable thickness. In this instance the cabinet is indicated as made of wood. The pulley 40 17 is arranged upon the shaft of the roll 33, and the belt 22 connects the pulleys 17 and 18, as in the construction hereinbefore described.

The operation is substantially similar to 45 the operation of the preferred construction hereinbefore described; pulling down on the toweling unwinds the same from the roll 33, and, through the pulleys 17 and 18 and belt 22, operates the winding up roll 14 at a greater speed, causing the toweling to 50 be rapidly and smoothly wound on said roll 14. The heavy roller resting on top of the roll of toweling 8 prevents the toweling from being moved too easily off from said 55 roll.

I prefer to construct the roll 14, and the roll 33, when said roll is used, so that the same may be freely removed from the cabinet and replaced by another roller, without 60 disturbing the position of the pulleys 17 and 18 and belt 22.

For this purpose I mount the pulley 18 upon a short shaft 37 mounted in a suitable bearing 38 in the wall of the cabinet. This 65 shaft projects into the interior of the cas-

ing and is provided with a square or polygonal end 39. The roll 14 is provided on its end with a socket 40 into which the end of the shaft 37 projects, so that by rotating the shaft 37 the roll 14 is turned therewith. 70

The opposite end of the roll 14 is provided with a cylindrical socket 41 and a spring controlled pin 42, mounted in a suitable socket 43 arranged in the wall of the cabinet. The pin 42 has a stem projecting 75 outside of the cabinet and preferably provided with a head 44 which may be grasped for the purpose of pulling said pin back into the socket, thereby permitting the contiguous end of the roll 14 to be moved 80 towards the adjacent wall of the cabinet, and the opposite end to be released from the shaft 37.

When the modified construction shown in Figures 6 and 7 of the drawings is employed 85 the shaft 33 and the upper part of the cabinet may be held in place by devices similar to those already described for holding the shaft 14 (Figure 6). The roll in the upper part of the cabinet, from which the towel is pulled by the user and which is provided with the driving pulley for the lower or winding up roll, may be conveniently designated the "towel dispensing 90 roll", or, considering it with reference to the lower roll 14, it may properly be designated as the "driving roll", as by its rotation it drives the winding up roll through the pulleys and belt hereinbefore referred to. 95

I do not limit myself to the details of the construction herein shown and described, as the same may be varied or modified in many particulars without departing from my invention. 100

I claim as my invention:

1. A towel cabinet having in combination a towel dispensing roll from which clean toweling is adapted to be drawn from a separate towel supply, a wind up roll spaced below the dispensing roll and having a 110 reverse movement, and a friction drive directly connecting said dispensing roll with said wind up roll, said friction drive being arranged to rotate the wind up roll in towel rolling direction as the dispensing roll rotates in towel dispensing direction and permitting slippage between said rolls and backward movement of said wind up roll and means for preventing the clean 115 part of the towel from contacting with the soiled portion thereof. 120

2. A towel cabinet having in combination a towel dispensing roll from which clean toweling is adapted to be drawn from a separate towel supply, a wind up roll spaced below the dispensing roll and having a 125 reverse movement and a belt drive for transmitting motion from said dispensing roll to said wind up roll, said belt drive being arranged to rotate the wind up roll 130

in towel rolling direction as the dispensing roll rotates in towel dispensing direction, said belt permitting slippage between said rolls to compensate for the varying diameters thereof and allow said wind up roll to be revolved backwardly for the purpose set forth and means for preventing the clean part of the towel from contacting with the soiled portion thereof.

10. 3. A towel cabinet having in combination a towel dispensing roll from which clean toweling is adapted to be drawn from a separate towel supply, a wind up roll spaced below the dispensing roll and having a reverse movement, a crossed belt drive for transmitting power from the shaft of said dispensing roll to said wind up roll, said belt drive being arranged to rotate the wind up roll in towel rolling direction as the dispensing roll rotates in towel dispensing direction, said belt allowing slippage between said rolls to compensate for their varying diameters and to allow said wind up roll to be reversed, said rolls through the crossing of said drive belt revolving in opposite directions and means for preventing the clean part of the towel from contacting with the soiled portion thereof.

4. A towel cabinet comprising, in combination, an upright casing having an open front, and a clean toweling holding compartment arranged in its lower part, a towel dispensing roll mounted in bearings in the upper part of the casing, a wind-up roll arranged below the open front of the casing, means for guiding the toweling from the holding compartment, over the dispensing roll, to the wind-up roll, and a friction drive between said dispensing roll and said wind-up roll, said drive being arranged to permit slippage between said rolls, for the purpose set forth.

5. A towel cabinet comprising, in combination, an upright casing having an open front, and a clean toweling holding compartment arranged in its lower part, a towel dispensing roll mounted in bearings in the upper part of the casing, a wind-up roll arranged below the open front of the casing, means for guiding the toweling from the holding compartment, over the dispensing roll, to the wind-up roll, belt pulleys arranged upon the shafts of said dispensing and wind-up rolls and a driving belt extending over said pulleys and arranged to permit slippage between said rolls, for the purpose set forth.

6. A towel cabinet comprising a casing having a receptacle in its lower portion for the clean towel, a dispensing roll in the upper portion of said casing and over which the web of clean towel is passed, a soiled towel take-up roll mounted intermediate to said clean towel receptacle and said dispensing roll, the web of clean toweling

being drawn outwardly from said dispensing roll to a point in front of the cabinet and from thence passing to said take-up roll, and a friction drive between said dispensing and take-up rolls adapted for slippage to compensate for the increasing diameter of said take-up roll.

7. A towel cabinet comprising a casing having an opening in its front wall through which the user may have access to the towel and a compartment for the soiled towel below said opening, a take-up roll mounted in said compartment over which clean toweling is adapted to be drawn from a separate towel supply, a dispensing roll for the clean towel mounted in the upper portion of said casing in position to deliver the web of clean toweling through said opening at the front of said casing, a friction drive connecting said dispensing roll with said take-up roll, said drive allowing said take-up roll to be reversed by pull of the user on the soiled portion of the towel, and said take-up roll being revolved to wind up the slack of soiled towel when a pull is applied by the user to the depending clean portion of the towel.

8. A towel cabinet comprising a casing having an opening in the upper front portion thereof through which the user may grasp the clean towel, and a compartment for the soiled towel below said opening, a take-up roll for the soiled towel mounted in said compartment over which clean toweling is adapted to be drawn from a separate towel supply, the forward wall of said compartment below said opening extending above said take-up roll, a dispensing roll for the clean towel mounted in the upper portion of said casing for delivering a web of the clean towel through said opening to the user, a friction drive between said dispensing roll and said take up roll, said drive allowing said take up roll to be reversed and a loop of the soiled towel to rest on said wall and depend outside said casing, and said take-up roll being revolved to wind up said loop of soiled towel when the user applies a downward pull to the web of clean towel.

9. A towel holder having in combination a towel dispensing roll over which clean toweling is adapted to be drawn from a separate towel supply in the upper portion thereof, a take up roll mounted for unrestricted movement in either direction in the lower portion, said holder having an opening between said rolls through which the user may grasp and pull the web of towel, a friction drive between said rolls, backward pull of the user on the soiled towel reversing said take-up roll to allow the formation of a depending loop of towel at the front of said holder, down pull of the user on the clean towel revolving said take-

up roll to wind up the soiled towel, the increasing diameter of the take-up roll causing a faster winding of the slack soiled towel than the delivery of the clean towel and thereby winding up said depending loop of soiled towel.

10. A towel holder having in combination a clean towel dispensing roll from which clean toweling is adapted to be drawn from 10 a separate towel supply, a take-up roll mounted for unrestricted movement in either direction, and a soiled towel compartment in which said take-up roll is mounted, a space being provided between said rolls 15 for the user to grasp and pull the clean towel outwardly and reverse the direction of movement of the take-up roll to form a loop of towel at the front of said holder, a friction drive between said rolls permitting 20 said reverse movement of the take-up roll and allowing slippage to compensate for the increasing diameter of the take-up roll, outward pull of the user on the clean towel operating said take-up roll through said

friction drive to wind up the soiled towel 25 and the loop formed therein.

11. A towel holder having in combination a towel dispensing roll from which clean toweling is adapted to be drawn from a separate towel supply, a soiled towel compartment, a take-up roll mounted for unrestricted movement in either direction in 30 said compartment, a friction drive between said rolls, said holder having an opening through which the user may grasp and pull 35 the clean towel, said compartment having a wall over which a loop of the towel may depend, the increasing diameter of the take-up roll winding up the soiled towel faster than the delivery of the clean portion and 40 compensating for any accumulation of soiled towel on the wall of said compartment, pull of the user on the clean towel operating to revolve said take-up rolls to 45 wind the soiled towel thereon.

In witness whereof, I have hereunto set my hand this 9th day of August, 1921.

FRANK M. STEINER.
